(57) **CLAIM**

I claim the ornamental design for a pepper holder, as shown and described.

DESCRIPTION

FIG. 1 is a front perspective view of a pepper holder showing my new design;

FIG. 2 is a side view thereof which is a mirror image of the opposite side view thereof;

FIG. 3 is a front view thereof;

FIG. 4 is a rear view thereof;

FIG. 5 is a top view thereof;

FIG. 6 is a bottom view thereof;

FIG. 7 is a front perspective view of my new design claiming only a portion of the design;

FIG. 8 is a side view thereof which is a mirror image of the opposite side view thereof;

FIG. 9 is a front view thereof;

FIG. 10 is a rear view thereof;

FIG. 11 is a top view thereof; and,

FIG. 12 is a bottom view thereof.

The broken lines in FIGS. 7-12 are for illustrative purposes only and form no part of the claimed design.
